UNITED STATES PATENT OFFICE.

WILLIAM C. SCHAPER, OF ST. LOUIS, MISSOURI.

METALLIC LATHING.

SPECIFICATION forming part of Letters Patent No. 536,234, dated March 26, 1895.

Application filed August 11, 1894. Serial No. 520,029. (No model.)

To all whom it may concern:

Be it known that I, WILLIAM C. SCHAPER, of the city of St. Louis, State of Missouri, have invented certain new and useful Improvements in Metallic Lathing, of which the following is a full, clear, and exact description, reference being had to the accompanying drawings, forming a part hereof.

My invention relates to an improved metallic lathing, and consists in the novel features of construction that will be hereinafter described and claimed.

The object of my invention is to construct from single sheets of metal a metallic lathing that is simple, durable, inexpensive, especially strong, and that requires less plaster to a given space than is required by metallic latings of other constructions.

A further object of my invention is to construct a lathing that will be especially efficient in holding the mortar in place upon its face.

Referring to the drawings: Figure 1 is a plan view of a section of my improved metallic lathing. Fig. 2 is a sectional view on the line 2-2 of Fig. 1. Fig. 3 is a sectional view on the line 3-3 of Fig. 1. Fig. 4 is a sectional view on the line 4-4 of Fig. 1. Fig. 5 is a sectional view on the line 5-5 of Fig. 1. Fig. 6 is a plan view of a portion of a modified form of my improved metallic lathing. Fig. 7 is a sectional view on the line 7-7 of Fig. 6. Fig. 8 is a sectional view on the line 8-8 of Fig. 6. Fig. 9 is a sectional view on the line 9-9 of Fig. 6.

Referring by numerals to the accompanying drawings, 1 indicates the body or sheet of metal out of which the lathing is formed, it being of suitable thickness. The method of forming the corrugations, slits, lips, &c., in the sheet metal body may vary, as various methods such as stamping, pressing, or passing the sheet metal bodies through rollers specially formed will accomplish the desired result.

The shaded portion, indicated by the numeral 2, is that portion that rests or engages directly against the rafters, boards, or to whatever the lathing is secured, and may be properly termed the base of the lathing. This base 2 remains intact and occupies the plane originally occupied by the upwardly bent portions of lathing. At stated distances in the

section 1 and extending in horizontal alignment are pairs of upwardly projecting lips or corrugations 3, the inner faces of said corrugations being indicated by the numeral 4. The ends of these corrugations are rounded, as indicated by the numeral 5, and in the rear of these corrugations at the point where they turn upward from the base 1 is formed a longitudinal slit 6, the edge 7 of which is bent into a plane with that of the inner edges of the corrugations. This will necessarily form depressions or valleys 8 in the longitudinal corrugations 3.

Strips 9 are preserved between the corrugations 3 and in the same plane as the base 2. The portion 10 of the section 1 is bent into a plane approximately half way between that of the base 1 and of the upper inner edges 4 of the corrugations 3.

In the formation of the corrugations in the section 1, I have found it desirable to alternate said corrugations in their parallel lines, though if desired said corrugations may be formed in parallel lines in both directions.

In the portion 10 and between the pairs of alternated corrugations 3 are triangular apertures 11, the edges of which are bent in a vertical plane, or at right angles to the portion 10, said up-turned portions being indicated by the numeral 12.

In the modified form shown in Fig. 6, the strip 9 is dispensed with, the corrugations 3 being bent up from a centrally formed slit 13.

In the practical use of my improved lathing, it is applied to the interior walls and ceiling of buildings as is ordinarily the practice, and the mortar applied directly thereto. As said mortar is applied to my improved lathing, the same being plastic, will enter the space between the edges 4 of the lips or corrugations, and as pressure is applied to said mortar it will contact with the strip 9 and be deflected in opposite directions thereby. By reason of this deflection, a portion of the mortar will engage beneath the lips or corrugations 3 and when said mortar becomes hardened will be very firmly keyed or held in position upon the lathing. A portion of said mortar will also enter the slits beneath the portions 7 and also through the triangular apertures 11. All this, it will be plainly seen, tends to firmly position the mortar in the

proper position upon the lathing and reduce the liability of the same becoming broken and disengaged therefrom to a minimum.

By bending the major portion of the section 1, or the portion indicated by the numeral 10, into a plane above the base portion, it will be seen how a lesser quantity of mortar is required to cover a given surface than if metallic lathing such as is commonly in use be employed. It will also be seen how by bending the body of the section 1 into two different planes or bases, the sections or bodies will be greatly increased in strength and lasting qualities.

Thus I have constructed a metallic lathing that possesses superior advantages in point of simplicity, durability and general efficiency.

What I claim is—

1. A metallic lathing having its body portion bent into differential planes, and corrugations bent from the lowermost plane upward in such a manner that their inner edges face each other, said corrugations being provided with a slit and lip at the juncture of the corrugation and the body portion.

2. A metallic lathing, consisting of a sheet of metal having its body bent into differential planes, alternating pairs of corrugations or lips bent upward from the lowermost plane of the body portion, lips formed by slitting

the rear of these corrugations, and triangular apertures, the edges of which are bent at right angles to the body portion, said triangular apertures being interspersed between alternating pairs of corrugations.

3. A metal lathing, consisting of a sheet of metal having its body bent into differential planes, pairs of lips or corrugations bent from the lowermost plane in such a manner as to leave a deflecting strip between said lips or corrugations, and lips formed by slitting the rear sides of the corrugations.

4. A metallic lathing, composed of a single sheet of metal, pairs of lips or corrugations having rounded ends bent upward from the body portion, a continuous corrugation or portion, such as 10, bent into a plane above the plane of the portion from which the lips or corrugations are bent, and triangular apertures formed in said continuous corrugation, the edges of said triangular apertures being bent at right angles to the continuous corrugation 10.

In testimony whereof I affix my signature in presence of two witnesses.

WILLIAM C. SCHAPER.
